TELEDICTAPHONE

Otto H. Schulz, Oakland, Calif.

Application August 28, 1934, Serial No. 741,765

22 Claims.

(Cl. 179—6)

This invention, an automatic tele-dictaphone, combines all of the advantages of the telephone and dictaphone, automatically converting the usual telephone into a voice recording device when the party called does not answer the telephone, and permitting a message to be delivered in the absence of the party called.

This invention is useful in many ways and under many conditions, since it is designed to permit the delivery of messages, telegrams, letters, orders, in the form of Morse or Continental code, or voice, from either wired or wireless telephone or telegraph, to any remote point where the invention is installed. A person calling another party may deliver their message, or leave a record of their call, an executive may dictate letters from his home or any remote point to his office, or a telegram may be recorded without waiting for an answer to the telephone.

Under existing methods it is necessary to arrange special connections, such as connecting the telephone receiver to a dictaphone, or set predetermined switches to obtain a record of a call, while with this invention no changes are necessary, the device always being ready for the reception of a message and automatically making the necessary connections when two telephone sets provided with this invention are linked together either directly or through a central station.

The voice recording device may be remotely located relative to the telephone or may be installed in the same cabinet with the telephone, and after a message is recorded, the entire arrangement resets itself to normal position ready for another call.

The objects of the invention are as follows:

First; to link two telephone sets together with necessary equipment for automatic recording of messages in the absence of the party called.

Second, To associate a telephone and a voice recording device in such manner that when no answer is obtained from a party called on the telephone within a predetermined period or number of signal impulses, that the voice recording devices will be automatically coupled to the caller's telephone set, so that a message may be delivered to a record in the form of a cylinder, disc, or film.

Third, To provide means for disrupting the operation of the voice recording device at any time when the answer party answers the telephone.

Fourth, To provide means for returning and resetting all control apparatus to normal inop-

erative position ready for another call when the caller hangs up their receiver.

Fifth, To provide means for coupling such voice recording device to any type of wired or wireless telephone or telegraph for operation by a pre-determined signal or series of impulses.

Sixth, To provide means where great amplitude is required, for amplifying the voice modulations to the recording device.

Seventh, To provide means for automatically maintaining the recording device or recorder out of contact with the recording medium at all times when the recording device is not controlled by a caller's telephone.

Other objects and advantages of the invention will become apparent as the following description is read on the drawings forming a part of this specification, and in which similar reference characters are used to designate similar parts throughout the several views, of which:

Fig. 1 is a wiring diagram of the invention shown in its simplest form as associated with a two-subscriber magneto line of the bridging type.

Fig. 2 is a detail view of the operating pawl connection.

Fig. 3 is a fragmentary view of the selector disc showing the teeth and idle space for limiting the movement of the disc or ratchet.

Fig. 4 is a modified form of wiring diagram adapting the invention to telephone circuits which include a series condenser.

Fig. 5 is an amplifying diagram for amplifying the voice modulations.

Fig. 6 is a wiring diagram of a wireless or radio receiving circuit with the invention applied thereto.

The invention includes any type of wired or wireless telephone circuit, such as magneto, common battery, automatic, or other modified forms and is applicable to any type or arrangement by modification of the equipment and wiring to suit the specific hook-up, and consists of a switching arrangement automatically actuated by the signaling system or the telephone set or radio transmitter of the caller or person calling, connecting a voice or sound recording device in circuit with the caller's telephone set or radio transmitter, so that a message may be delivered without the presence of anyone at the answer phone or receiving circuit.

The telephone circuits will not be described in detail since the various circuits are well understood in the art and detailed information can be obtained from various publications devoted to "Telephony".

55

In simple form, a completed telephone circuit consists of two telephone sets connected in circuit through a central station by means of plugs 10 and cords 11 through suitable jacks 12 and 13, the central office equipment not being shown other than the above-mentioned plugs, cords and jacks. The radio circuit consists of a transmitter, and a receiver tuned to the same frequency.

The two telephone sets are identical, one telephone set consisting of a transmitter 14, a receiver 15, a receiver hook 16 and such other apparatus, coils, condensers and batteries as may be required for the particular type of circuit, and is designated as the "Caller" phone, and the same parts on the "Answer" phone are designated by the characters 17, 18 and 19, the caller telephone being designated by the letter "C", and the answer phone by the letter "A". The circuit between the two telephone sets is completed 20 through the wires 20, 21, 22, and 23.

The circuit also includes the call bells 24 and 25 for telephone operation over wired circuits, and which bells may be operated by the magneto 26 or by the central station operator, or automatically, depending on the system of wiring.

In the wiring diagram, Fig. 1, it will be noted that the caller's receiver 15 is removed from the hook 16 permitting the hook to bridge the circuits to the transmitter 14 and receiver 15 through contacts 28 and 29, while the answer telephone hook 19, being depressed by the weight of the receiver 18, maintains the circuit to the transmitter 17 and receiver 18 open, contacts 30 and 31 being open. Obviously, the hook actually operates a switch for making these contacts and which switch is omitted for purposes of clarity.

The parts so far described are standard and do not form a part of the invention except in the combinations described and claimed, and the 40 circuit so far described is only modified for this invention by the inclusion of selector means in the signaling circuit and the extension of the main line circuit.

The automatic selector means may be applied to one or both telephones, as it is not necessary for any telephone set to have the selector to operate the selector of another phone, however, in the wiring diagram, both sets are shown equipped therewith, so as to fully explain the 50 mutual operation between two sets.

The automatic selector means is identical for each telephone set where the voice or sound recording device is installed and consists respectively of the relays 32 and 33 having one terminal connected through wires 34 and 35 respectively to the terminal telephone lines 20 and 21 as indicated at 36 and 37, their other terminal being in series with the respective contacts 38 and 39 through wires 40 and 41. It will be noted that 60 no source of current is included directly in the circuit between the two relays 32 and 33, and when the two hook levers 16 and 19 are both depressed, that both relays are grounded by co-operation of these levers through a suitable 65 switch (not shown) with the contacts 38 and 39.

The primary circuit for the relays consists of the respective batteries 42 and 43 having one terminal connected respectively to the connections 34 and 35, and the other terminal connected to the contacts 44 and 45 which cooperate with the receiver hooks in their raised or released position. Thus the battery 42 completes a circuit 70 only with relay 33, and battery 43 with relay 32, and since the batteries are connected in parallel, 75

current can only flow when one receiver hook is depressed and the other released.

The relay secondary circuits consist of the armatures 46 and 47 which are respectively connected through wires 48 and 49 to contacts 50 and 51 for cooperation with the receiver hooks 19 and 16 in depressed position, and the armature contacts 52 and 53 are connected through the respective batteries 54 and 55 to one terminal of the respective electro-magnets 56 and 57 through wires 58 and 59, the other terminals 60 and 61 being connected to ground 62. The armatures 63 and 64 are normally retracted by the springs 65 and 66, the armatures normally maintaining the respective stop pawls 67 and 68 and operating pawls 71 and 72 out of engagement with the respective selector ratchets 69 and 70.

The pawls cooperate with the armatures through the connectors 73 and 74, which are slotted at one end as shown at 75 in Fig. 2, the 20 pawls being urged by the springs 76 to cooperate with the ratchets when brought into association by the armatures.

The pawl operating mechanism consists of the respective electro-magnets 77 and 78 connected 25 through wires 79 and 80 in series with the signaling or bell ringing circuits 81—82 and through wires 83 and 84 to the return or ground side 22—23 of the telephone circuit. The respective pawls 71 and 72 are connected to the terminal 30 ends of the armatures 85 and 86 of the electro-magnets 77 and 78 and are reciprocally operated thereby.

The ratchets or selector discs 69 and 70 are each provided with a multiplicity of fine teeth 87 35 as shown in Fig. 3, the pitch being approximately equal to the stroke of the armatures at the point of connection whereby each impulse advances the ratchet one tooth. These discs are resisted by springs 88 and 89 which return the ratchets to 40 their normal position when the pawls are released.

The switching mechanism for the voice or sound recording device consists of quick-throw switches 90 and 91, which cooperate with the pins 92 and 93 on the respective ratchets 69 and 70 45 and close to contacts 94 and 95, these switches being connected to one terminal of a source of current, such as a power line 96, the other terminal 97 of which is connected to the respective contacts 94 and 95 through the respective primaries 98 and 99 of transformers 100 and 101. It will be understood that battery circuits may be used, and all magnets and relays are adapted to the specific current used, whether direct or alternating, and the specific current will be used 55 which is best adapted to the specific circuit, since in some cases an alternating current may be desirable using alternating current magnets and relays, while other cases may be best suited to direct current with direct current magnets and 60 relays.

The voice or sound recording means consists of recording devices 102 and 103, which may be of the "Dictaphone" type or any other well known type such as a magnetically actuated diaphragm 65 operating recording needles or points 104 which cooperate with the record blank, such as cylinders 105 and 106, and which cylinders are driven by the respective motors 107 and 108, these motors being shown as driven through the medium of 70 the secondary current set up in the secondaries 109 and 110 of the transformers 100 and 101, through wires 111 and 112, suitable reduction gearing (not shown) being provided between the motor and the cylinder, this recording means being 75

of conventional type and not requiring detailed description.

In connection with the above, it will be understood that photographic film may also be used for the record blank with the record formed through the medium of a photo-electric cell, and which process is also well known.

The recording devices 102 and 103 are normally maintained out of cooperation with the record blank or cylinders 105 and 106 by means of armature levers 113 and 114 which are pivotally mounted at 115 and 116 and retracted by the springs 117 and 118, these armatures being in cooperative relation to the electro-magnets 119 and 120 which are connected in circuit with the secondaries 109 and 110 of the transformers 100 and 101 as shown.

The voice recording circuit consists of relays 121 and 122 which are also connected in circuit with the secondaries 109 and 110 of the transformers 100 and 101, the armatures of these relays closing a circuit across the telephone circuit 20—21 and 22—23 through wires 123 and 124, and 125—126.

The circuit so far described is but one form of circuit using both direct and alternating current electro-magnets and relays, and showing a completely operative circuit, the operation of which is as follows:

With both receivers 15 and 18 hung on their respective receiver hooks, all circuits are broken. One receiver 15 is removed from the hook 16, as shown, closing the circuit to the receiver 15 and transmitter 14, and coincidentally closing the circuit through contact 45, battery 43, line 21, calling the operator O at the central station, who completes the circuit through jacks 12—13 by means of cords 11 and plugs 10, (or the circuit is automatically completed with automatic systems) through wire 20, wire 34, relay 32, contact 38, hook 19, line 22—23 or ground, to hook 16.

Energization of relay 32 closes the circuit through hook 19, wire 48, armature 46, contact 52, battery 54, magnet 56, wire 60, to ground 62, drawing armature 63 down and releasing pawls 67 and 71 to cooperate with ratchet 69. Caller C or operator O then by suitable means, such as magneto 27 rings subscriber or answer party A in the usual manner, the impulse passing through the signal or bell circuit 25, wire 81—79, through magnet 77 and wire 83 oscillating armature 85 and pawl 71, rotating disc 69 against the resistance of spring 88, the pawl 67 retaining the disc against retrograde movement. If during the course of the ringing receiver 18 should be lifted, the circuit to magnet 56 will be broken at contact 50 and the spring 65 will release the pawls from the ratchet and the ratchet will immediately return to its normal position under the urging of 88.

If the call is not answered and the receiver remains on the hook, the ratchet is rotated until pin 92 engages the switch 90 which is urged until the shifting spring 127 throws the switch to contact 94, following which, the pawl 67 rides in the idle space 169, preventing further movement of the ratchet, but preventing its release, and as this pawl does not pick up the stroke of the pawl 71, the ratchet idles in its position, and remains in that position until either the receiver 18 is lifted off its hook, or the receiver 15 is placed on its hook.

Switch 90, closing to contact 94 closes the main power circuit through the primary 98 of transformer 100, inducing a current in the secondary which starts and operates motor 107, coincidentally 75 rotating the record 105, simultaneously energiz-

ing magnet 119, which draws armature 113 down, bringing the recording point 104 in contact with the face of the blank 105, the recording diaphragm or coil and point together with the frame 128 which is hinged at 129, gravitationally cooperating with the cylinder or blank 105.

Coincidentally, magnet 121 is energized, closing the voice or sound circuit to the recorder through wire 123, contact 130, armature 131, recorder 102, and wire 124 to line 22.

The recording device is now in operation and caller C delivers their message which is recorded on the cylinder, after which caller hangs up their receiver 15, thereby breaking the circuit at 45, de-energizing relay 32, breaking circuit at 52 and 15 through magnet 56, releasing armature 63 which is retracted by spring 65, retracting pawls 67 and 71, releasing ratchet 69 which is counter-rotated by spring 88, pin 92 in its counter-movement engaging the opposite side of lever 132 and reversing 20 switch 90, breaking contact at 94, disrupting operation of motor 107, releasing armature 113 to lift the recorder 102 from the cylinder and breaking the circuit to the recorder at 130.

This same disruption of recording circuit occurs 25 when the receiver 18 is lifted, and both telephone stations operate in the same manner. The recording device at one station can be operated by another station which is not so equipped, except for a battery 43 and contact 45.

A cylinder or disc changer, (not shown) may be incorporated where a great amount of recording service is desired:

In Fig. 4, a modification is shown in which the interposed condenser 133 will not permit operation of the recorder selector by direct current, such a circuit requiring an alternating current for operation of the selector.

The modification also includes manually controlled means for operating the selector.

This modification consists of the usual transmitter 17, receiver 18, hook 19, together with the line 134 having the condenser 133 in series. The selector means consists of the alternating current magnet 135 which is connected in series through 35 contact 136, wire 137, battery 138, magnet 135, wire 139, armature 140, make-and-break contact 141, primary 142 of transformer 143, switch 144 to ground or lever 145.

Each time switch 144 is closed while receiver 18 is off the hook, a series of impulses is transmitted to operate the selector at the other station through the secondary 146, line 134 and condenser 133, operating the magnet 135. The balance of the circuit is similar to that described for 50 Fig. 1.

In Fig. 5, a modification is shown in which the voice modulations are amplified, the modulations being transferred from the induction coil primary 147 to the secondary 148 which is tuned to a predetermined frequency by the condenser 149, the modulations being impressed on the grid 150 of the radio amplifying tube 151, the incoming modulations being amplified in the customary manner, the plate 152 being connected through 60 suitable audio frequency transformers 153 and succeeding stages of amplification to the recorder 102, a suitable current supply 154 being provided.

This diagram also shows a reproducer 155 which may be incorporated for manual cooperation, the usual operating means and switch means (not shown) being incorporated therewith. With this arrangement, the messages may be reproduced without removal of the record.

Fig. 6 is another modification showing the in- 75

vention as applied to radio or wireless transmission, using any standard transmitting and receiving circuits, and modifying them to suit the particular hook-up, a simple radio frequency receiver being shown.

A simple arrangement is shown in which a carrier wave 156 is first impressed on the antennae 157 and transferred from the antenna coil 158 to the grid coil 159 which is tuned by means of the condenser 160 to the frequency of the incoming wave and left at this setting, this incoming carrier current being amplified through suitable radio tubes 161 and 162 and transformer 163 to plate 164, the circuit so far described being standard, and well known in the art.

When the receiver hook 19 is depressed, plate 164 is connected in series with a sensitive relay 165, battery 166, electromagnet 77 to ground 167, closing a circuit through the receiver hook 19, armature 46, battery 54, electromagnet 56, bringing the pawls 67 and 71 into engagement with the disc or ratchet 69.

The frequency of the incoming wave is too high to affect the driving pawl 71, and the effective pull of the electromagnet is made such as to operate the pawl only under intensified current and therefore is actuated only by modulations or audio frequency impulses.

When a series of dots 168 or impulses, (which may be made in the form of a specific signal if desired) is impressed on the antenna, the audio frequency fluctuations and intensity of current set up by the modulations operate the selector magnet 77, operating the selector as previously described.

In all other respects the device is operated similarly to those previously described. After the selector has attained a predetermined position after throwing the switch, it cannot be moved farther due to the omission of teeth at one point 169, which prevents operation of the pawl, and voice, sound, code, or telegraph signals may be recorded.

When the wave length or frequency of the transmitting station is changed, the device automatically returns to its normal position, resetting itself, and lifting of the receiver hook automatically disrupts operation of the selector.

It will be noted that with the receiver on hook 19, (Fig. 6), a circuit is closed from plate 164 through wire 170, switch 171, contact 172, through magnet 165 and recorder 102 in parallel to battery 166, and coincidently, with energization of magnet 165, another circuit is closed through the receiver hook 19, armature 46, battery 54 to place the pawls in cooperation, and that when the receiver hook is released, the circuit to the magnet 165 is broken as also to magnet 56, and a circuit completed through plate 164, through switch 171, contact 173, receiver or loud-speaker 174 to battery 166, so that the recorder is made inoperative when the message is audibly received.

It will be understood that variations in method, circuits, adaptation, arrangement and equipment, which variations are consistent with the appended claims, may be resorted to without detracting from the spirit or scope of the invention or sacrificing any of the advantages thereof.

I claim.

1. In combination, two telephone sets and a circuit therefor, a voice recording device including an electrically actuated recorder in cooperative relation to one set, means made operative by release of the receiver hook of the other set and inoperative by the release of the receiver hooks

of both sets and actuated by electrical impulses set up in the signaling system for the one set electrically associating the other telephone set with the recorder of said recording device when the receiver of the one set remains unreleased for a predetermined signaling period, and made inoperative and causing the means to return to normal position when the receiver hook of the other set is depressed.

2. In combination, two telephone stations each including transmitter, receiver, signaling device, receiver hook, a sound recording device including an electrically actuated recorder, and selective means selectively associated with the depressed and raised positions of the receiver hooks and actuated by electrical impulses in the circuit of the signaling device, associating one telephone set exclusive of sound recording device with the recording device of the other set and exclusive of the transmitter and receiver thereof when the signaling device of the other set remains unanswered for a predetermined oscillatory period of said signaling device.

3. In combination, two telephone stations each including transmitter, receiver, signaling device, receiver hook, a sound recording device including an electrically actuated recorder, and selective means selectively associated with the depressed and released positions of the receiver hooks and actuated by electrical impulses in the circuit of the signaling device associating one telephone station exclusive of its sound recording device with the recording device exclusive of the transmitter and receiver of the other station when the signaling device of the other station remains unanswered for a predetermined oscillatory period, and disrupting the operation of the selective means and permitting its return to normal position when the signaling device of the other station is answered, and means for returning the selective means to its normal position.

4. In combination, two telephone stations each including transmitter, receiver, signaling device, receiver hook, a sound recording device including an electrically actuated recorder, and selective means selectively associated with the depressed and released positions of the receiver hooks and actuated in association with electrical impulses in the circuit of the signaling device associating one telephone station exclusive of its sound recording device directly electrically with the recording device of the other station exclusive of the other elements of the other station when the receiver of the other station remains inoperative for a predetermined signal period, and disrupting the operation and resetting the selective means to normal position when the receiver of the other station is operated, and disrupting the operation and resetting the selective means when the cooperative relation of the two stations is terminated.

5. In combination, two telephone sets and a circuit therefor, each set including a transmitter, a receiver, a receiver hook and a signaling system, a sound recording device including an electrically actuated recorder and a record blank for each set, a selective switch for each set controlling the recording device associated therewith and controlled by the receiver hook of the other set, said selector switch being actuated by electrical impulses in the circuit of the signaling system of the other set, said selective switch automatically electrically associating the other set directly with the recording device of the one set and oper-

5

70

75

ating the device through a suitable source of current controlled by the selector switch.

6. In combination, two telephone sets and a circuit therefor, each set including a transmitter, a receiver, a receiver hook and a signaling system, a voice recording device including an electrically actuated recorder and a record blank for each set, a selector switch for each set controlling the recording device associated therewith and controlled by the receiver hooks, said selector switch being actuated by electrical impulses set up in the signaling system of one set, said selector switch automatically electrically connecting the one set directly with the recorder of said recording device of the other set and operating the device through a suitable source of current controlled by the selector switch, and means resetting said selector switch to normal position and disrupting the current when operation of the one set is discontinued.

7. In combination, two telephone sets and a circuit therefor, each set including a transmitter, a receiver, a receiver hook and a signaling system, a sound recording device including an electrically actuated recorder and a record blank for each set, a selector switch for each set controlling the recording device associated therewith and controlled by the receiver hooks, said selector switch being actuated by electrical impulses set up in the signaling system of the other set, said selector switch automatically electrically connecting the other set directly with the recorder of said recording device of the one set and operating the recording device through a suitable source of current controlled by the selector switch of the one set, and means resetting the selector switch to normal position and disrupting the source of current when the receiver hook of the one set is released as by answer of the signal of the signaling system of the other set.

8. In combination, two telephone sets and a circuit therefor, each set including a transmitter, a receiver, a receiver hook and a signaling system, a sound recording device including an electrically actuated recorder and a record blank for each set, a selector switch for each set controlling the recording device associated therewith and controlled by the receiver hooks, said selector switch being actuated by electrical impulses set up in the signaling system of the other set, said selector switch automatically electrically connecting the other set directly with the recorder of said recording device of the one set and operating the recording device through a suitable source of current controlled by the selector switch of the one set when the signaling system remains unanswered, and means resetting the selector switch to normal position and disrupting the source of current when the receiver hooks are in any other position than the depressed position of the one set and the raised position of the other set.

9. In combination, two sound transfer sets each including sound transmitting means and sound receiving means and associated talking circuit, signaling means and control means for each set in circuit with the talking circuit; sound recording means including an electrically actuated recorder for each set; connective means for each set controlled by the control means and actuated by electrical impulses of the signaling means electrically connecting one set exclusive of its recording means directly with the recorder of the other set through the talking circuit after

a predetermined number of impulses, while the other set, exclusive of its recording means is in normal inoperative relation, said connective means being made inoperative through the control means by any change in electrically cooperative relation of the sets from that of the one set calling and the call being unanswered by the other set.

10. In combination with two stations linked by a talking circuit including a signaling system, and a switch for each station controlling the talking circuit, control means in parallel with each station and controlled by the switches of both stations, a sound recording system including an electrically actuated recorder for each station, a current supply for each recording system, a selector controlled by each control means and electrically actuated in circuit with the signaling system completing circuit between the recording system and its current supply at one station and coincidentally cutting the recorder directly in circuit with the talking circuit to the other station, said control means disrupting operation of the recording system when the switches at both stations are both in either open or closed position, and permitting actuation of the selector means only when the switches are respectively in open and closed positions.

11. In combination with two telephone stations linked by a talking circuit and including a signaling system and a receiver hook for each station; a sound recording system including an electrically actuated recorder, a record, and a current supply for each station, means actuated in circuit with the signaling system completing circuit from the current supply to the recording system and coincidentally cutting the recorder directly into the talking circuit at one station when the receiver hook at said one station remains depressed and the receiver hook at the other station is released and means resetting the selector means when said receiver hooks are both, either released, or depressed.

12. In combination with two telephone stations linked by a talking circuit and including a signaling system and a receiver hook for each station, a sound recording system including an electrically actuated recorder, a record, and a current supply, for each station; means actuated in circuit with the signaling system completing circuit from the current supply to the recording system and coincidentally cutting the recorder directly into the talking circuit at one station and moving said recorder into cooperation with said record when the receiver hook at said one station remains depressed and the receiver hook at the other station is released, and means automatically resetting the selector means and moving the recorder out of cooperation with the record when said receiver hooks are both, either released, or depressed.

13. In combination with two telephone stations linked by a talking circuit and including a signaling system and a receiver hook for each station; a sound recording system including an electrically actuated recorder, a record, and a current supply, for each station, control means electrically associated with each station controlled by the receiver hooks of both stations, selector means actuated in circuit with the signaling system and controlled by the control means, completing circuit from the current supply to the recording system and coincidentally cutting the recorder directly into the talking circuit at one station when the receiver hook at said one station remains depressed and the receiver hook at the other station is released, and

means resetting the selector means when said receiver hooks are both, either depressed, or released.

14. In combination with two telephone stations linked by a talking circuit and including signaling means and a circuit therefor and a receiver hook for each station; a sound recording system including an electrically actuated recorder, a record, and a current supply for each station, control means electrically associated with each station and controlled by the receiver hooks of both stations, selector means actuated in circuit with the signaling means and controlled by the control means completing circuit from the current supply to the recording system and coincidently cutting the recorder directly into the talking circuit at one station and moving said recorder into cooperation with said record when the receiver hook at said one station remains depressed and the receiver hook at the other station is released, and means resetting the selector means and moving the recorder out of cooperation with the record when said receiver hooks are both, either released, or depressed.
15. In combination with two telephone stations including a talking circuit and a signaling system, and a switch having two sets of contacts associated with each station; an automatic sound recording system including an electrically actuated recorder, a record, and a current supply, for each station; means electrically associated with the signaling system and controlled by the switches of both stations connecting the sound recording system of one station with its current supply and coincidently connecting the recorder of said one station directly across the talking circuit after a predetermined period of signaling from the other station while the switch of said one station is closed to one set of contacts and the switch of the other station is closed to the other set of contacts, changing the relation of either or both switches automatically returning the sound recording system to normally inoperative position and reset for a future call.
16. In combination with two telephone stations including a talking circuit and a signaling system, and a receiver-hook-actuated switch having two sets of contacts associated with each station; an automatic sound recording system including an electrically actuated recorder, a record, and a current supply, for each station; control means electrically associated with the talking circuit and controlled by the switches of both stations; selector means including switch means and electrically associated with the signaling system and controlled by the control means associated therewith connecting the sound recording system of one station with its current supply and coincidently connecting the recorder of said one station directly into the talking circuit after a predetermined period of signaling from the other station, and coincidently moving the recorder into cooperation with said record, and maintaining said connections while the switch of said one station is closed to one of its sets of contacts, and the switch of the other station is closed to the other of its set of contacts; changing the relation of either or both switches automatically returning the sound recording system and associated control and selector means and recorder to normal inoperative position and reset for operation with a future call.
17. In combination with two telephone stations including a talking circuit and a ringing circuit, and a receiver hook for each station; a magneti-

cally actuated control in circuit with each station end of the talking circuit and controlled by the receiver hooks of both stations; a selector operated in electrical association with the ringing circuit and associated with each control means and controlled thereby; a sound recording system having an electromagnetic recorder, a record, and a current supply, and controlled by said selector to operate the sound recording system and connect the recorder directly into the talking circuit, 10 said selector operating only at one station at which the receiver hook is depressed.

18. Automatic sound recording means for telephone systems comprising in combination with two telephone stations linked by a talking circuit and including a ringing circuit, and, a receiver hook for each station; a recording system including a record and an electro-magnetic recorder; means actuated by electrical impulses in the ringing circuit and controlled by the receiver 15 hooks of both stations automatically connecting the recorder directly electrically into the talking circuit, coincidently moving the recorder into cooperation with the record and causing operation of the recording system after a predetermined 20 period of ringing when the receiver hook at one station remains depressed and the receiver hook at the other station is released.

19. Automatic sound recording means for telephone systems comprising in combination with two telephone stations linked by a talking circuit and including a ringing circuit, and, a receiver hook for each station; a recording system including a record and an electro-magnetic recorder and means for driving said recording system; means actuated by electrical impulses in the ringing circuit and controlled by the receiver hooks of both stations automatically connecting the recorder directly electrically into the talking circuit, coincidently moving the recorder into cooperation with the record and actuating the driving means after a predetermined ringing period when the receiver hook of one station remains depressed and the receiver hook of the other station is released, and means automatically disrupting operation of, and returning and resetting the recording system to normal inoperative position when the relation of the receiver hooks is changed from that described.

20. Automatic sound recording means comprising, in combination with two telephone stations linked by a talking circuit and including a signaling system and, a receiver hook for each station; a sound recording system including a record, driving means, and an electro-magnetic recorder, for each station; means actuated in series with the signaling system and controlled through the talking circuit by the receiver hooks of both stations electrically connecting said recorder directly into the talking circuit, and coincidently moving the recorder into cooperation with the record, and starting operation of the driving means for operating the recording system at one station after a predetermined period of signaling when the receiver hook of said one station is depressed, and the receiver hook at the other station is released, and means automatically disrupting operation of said recording system, disconnecting the recorder from the talking circuit, and moving the recorder out of cooperation with the record when the relation of the receiver hooks is changed from that described.

21. A recording system comprising a talking circuit including two telephone stations having each a receiver hook normally in depressed posi-

tion; a mechanical type record, a recorder operable to cut a record trace thereon, for one station; means to effect recording movement of both the record and recorder, and automatic means controlling the means to effect recording movement in such a way that movement of neither the record nor recorder takes place when the receiver hooks of both stations are simultaneously both in either released or depressed position, said automatic means automatically connecting the recorder directly into the talking circuit and being actuated by signal impulses therein when the receiver hook of said one station remains depressed and the receiver hook of the other station is released and the one station is signalled.

22. A recording system comprising a talking circuit including two telephone stations having each a receiver hook; recording means including

a mechanical type record and operating means and an electrically actuated recorder therefor, for each station; selector means at each station operated through the agency of signal impulses in the talking circuit and controlled by the receiver hooks of both stations automatically connecting the recorder of one station directly into the talking circuit and starting the operating means to continuously operate the record when the receiver hook of the other station is released while the receiver hook of the one station remains depressed, and disrupting operation of the recording means when either the receiver hook of said one station is released, or, the receiver hook of the other station is depressed while the receiver hook of the one station remains depressed.
